LOW OIL CONTROL

John B. Harrison and Gilbert T. Adams, Memphis, Tenn., assignors to Rotary Lift Company, Memphis, Tenn., a corporation of Delaware

Application November 12, 1949, Serial No. 126,868

3 Claims. (Cl. 121—46)

1

Our invention relates to a low oil control or more specifically a control for a hydraulic lift or elevator which responds to an undesirably low level of hydraulic fluid to check the upward movement of the lift.

Almost all modern hydraulic lifts, and particularly those used for automobile servicing have one characteristic in common; each system contains two connected reservoirs for hydraulic liquid, and the raising of the lift is accomplished by admitting air under pressure to the fluid surface in one of the reservoirs resulting in the expelling of the liquid into the other reservoir. Thus, for example, in one common type of motor vehicle servicing lift the liquid—usually oil—is expelled, by compressed air, from an external tank to the cylinder of the lift ram to elevate the plunger and returns from the cylinder to the external reservoir as the plunger descends; and in another type the plunger, which is hollow, takes the place of the external tank from and back to which the liquid flows as the lift ascends and descends. The liquid flow through the connection is restricted as by a small orifice, elongated tubing, or any device which serves to provide resistance to flow. This structure or mode of operation has as one major advantage the avoidance of the jerkiness and uncontrollability of direct unrestrained pneumatic operation resulting from static friction, inertia, variations in moving friction, etc. The restricted liquid flow smooths the pneumatic drive in much the same fashion as a dashpot operates. It will be noted, however, that if the level of oil is low, as it is expelled from the first reservoir, the contents of this reservoir will be exhausted and air will blow directly into the second reservoir, so converting the drive to the direct and unrestrained pneumatic operation with all its disadvantages, amplified by the fact that the system is designed around the viscosity characteristics of the oil and not those of a gas.

The type of lift to which our control is intended primarily to be applied, although it is suitable for use with any of the forms of this pneumatically impelled hydraulic lift, is that known as the self-contained lift wherein the movable plunger forms the storage reservoir from which oil flows to the cylinder and returns from the cylinder through an orifice in the bottom thereof. Hydraulic fluid fills completely the outer casing or cylinder and in large part also the interior of the plunger when the lift is in its lower position. To raise the lift, air under pressure is admitted into the top of the plunger against the surface

2

of the oil contained therein and an even movement of the plunger is insured by restricting the orifice out of which the oil in the plunger must pass to the casing in order to permit the plunger to rise.

It will be evident that if air escapes from this orifice, the lift will be without the oil restraint and so be subject to the jerking discussed above. A secondary effect of this escape of air will be to introduce an air bubble into the annular space between the outer casing and the plunger, so providing a resilient cushion not subject to the restraint of the orifice which will permit a jerking start for all subsequent elevations until the bubble is vented off. One way, and one of frequent occurrence in the absence of any control, by which air may escape from the plunger is that, in the event of an insufficient oil supply within the casing, the plunger will lift above the surface of the oil, so permitting air to blow out through the orifice into the casing reservoir.

One object of our invention is to halt the raising of a hydraulic lift when the oil level is too low.

Another object is to indicate to the operator a too low oil level in a hydraulic lift by this premature cessation of movement.

Another object of our invention is to provide a novel control for a self-contained lift preventing the plunger from rising to such an extent as might permit the emission of air from the lower orifice thereof.

Another object of our invention is to provide a novel control which responds to an undesirably low level of hydraulic fluid in a lift during a raising operation to check the movement of the lift to prevent the total exhaustion of oil in the reservoir to which pneumatic pressure is being applied.

Still another object of our invention is to provide a novel control for a hydraulic lift which is responsive to a too low hydraulic fluid level in the course of a lifting operation and which shuts off the flow of air raising the lift at a point in the course of the lift prior to that point which would permit air to escape from the plunger.

Still another object of our invention is to provide a novel low oil control for a hydraulic lift of the self-contained type which is substantially more practical and longer lasting than any hitherto known.

Another object of our invention is the provision of a low oil control for a hydraulic lift which is simple and inexpensive in construction and sure in operation.

Other objects and advantages of our invention

will be apparent from the following description and drawings, in which:

Fig. 1 is a section through a self-contained type hydraulic lift in its lowered position, illustrating an embodiment of our invention in plan;

Fig. 2 is a vertical section through the valve portion of our invention;

Fig. 3 is a section similar to Fig. 1 through a self-contained hydraulic lift showing, however, the lift in elevated position and with an insufficient oil supply; and

Fig. 4 is a fragmentary plan of a modified form of our control, broken away in part to show a section through the valve.

A hydraulic lift of the self-contained type consists generally of a cylindrical casing 10 closed at its lower end by a wall 12 and provided with bearing rings 14 which receive and guide a cylindrical plunger 16. Packing 17 furnishes a liquid- and air-tight joint between the top of the casing and the wall of the plunger. The plunger is closed at its lower end by a plunger head 18 having a central opening 20 in which a thimble 22 is loosely inserted. An air pipe 24 connected at its upper end 26 to a valve and a source of air under pressure (not shown) enters the casing 10 axially through the bottom wall 12 thereof to admit or relieve the operating air under pressure. The thimble 22 possesses a central opening 28 and the air pipe extends upwardly from its point of entry into the bottom wall 12 of the casing through the hole 28 in the thimble 22 into the plunger and to a point above the normal oil level 30. The casing is usually sunk in a floor 29 so that the top edge is flush therewith, and an air vent passage 31 is provided to bleed off any air which may be entrapped between the plunger and casing. The passage is closed by a plug 33. It will be evident that as air is admitted into the space 34 above the normal level 33 of the oil, the plunger will be raised and the rate of this raising will be controlled not only by the pressure admitted to the space 34 but also by the velocity of flow of the oil from within the plunger 16 through the opening 20, particularly as this flow is restricted by the thimble 22.

A primary source of the jerky or bumpy operation of the lift arises from the fact that in moving the plunger from a stopped position there is a static frictional engagement between the plunger 16 and the packing 17 and it requires substantially greater air pressure to break this engagement than it does to maintain in movement the already moving plunger. Thus, were it not for the restricted outflow of the oil from the plunger, when the pressure reached a point sufficient to break this engagement the plunger would jerk suddenly upward, but the thimble, by restricting the outflow of oil, serves as a dashpot to control and steady the rate of elevation regardless of relatively great variances in pressure in the space 34.

Attempts have been made to provide low oil controls for this type of lift. They have usually taken the form of a buoyant valve situated adjacent the plunger head 18, so as to permit or cut off the flow of oil therethrough. It is apparent from the very nature of a low oil control which operates by preventing the exit of oil from the plunger that the valve controlled opening can be the only opening through the bottom plunger head. Otherwise there would not be the desired termination of movement. In such case a sliding seal must be effected between the pipe and the plunger head. Assuming the use of pack-

ing to obtain this seal as the most logical expedient, and any seal forming means would be subject to the same disability, there would be substantial wear between the pipe and the packing,

5 such that constant tightening or replacement would be required to maintain the necessary seal or, in other words, prevent the formation of a second opening. Furthermore, such packing would be only doubtfully, and then difficultly, accessible to the normally equipped garage or filling station. The packing would have to be in tight engagement with the exterior of the pipe over a travel of about 6 to 8 feet per elevation and the same distance per lowering. No packing 10 could stand up under the length of travel represented in several hundred elevations and under the pressures involved and maintain the necessary tight seal without frequent adjustment.

Furthermore, the control is intended to handle an emergency situation. A failure of the packing would not appear until the low oil control was called on to perform its function, and there would be consequently no signal that the seal was in need of adjustment.

15 Our invention accomplishes the halting of the upward travel of the plunger not by checking the flow of oil from the plunger but rather by checking the admission of air into the plunger and avoids the above difficulties attributable to wear 20 by effecting the necessary closure with a minimum of relative travel between the parts and by no relative movement at all if the oil level is properly maintained.

In the illustrated embodiment of our invention 25 a generally cylindrical valve body 48 having a longitudinal bore 41 therethrough and a threaded portion 43 is attached by the threaded portion to the upper end of the pipe 24. The upper portion 42 of the body is somewhat reduced in diameter to afford a shoulder 45 and has a ground or otherwise smoothly finished outer surface 44. This upper portion is perforated by a plurality of radial perforations 46 which constitute the ports for admitting and relieving the air in the space 30 34. A valve ring 48 is slidably mounted on this upper portion 42 and a snap ring 50 is situated at the upper end thereof so as to limit the travel of the valve ring. The relation between the snap ring 50 and the ports 46 is such that when the 35 valve ring is at its uppermost point of travel against the snap ring 50, the ports are uncovered, whereas at the lowermost point of travel of the slide ring 48 against the shoulder 45 of the body, the ports are closed. The upper end of the valve body likewise communicates with the interior space 34 of the plunger through the open end 52 of the bore 41 and a valve seat 54 is provided in the bore upon which a ball valve 56 may seat to close the end 52. The ball valve is retained in a 40 position close to the valve seat by pin 58.

The valve ring 48 has press fitted thereinto 45 downwardly extending arms 60 of a yoke 62 which is fixed at its lower end by a bracket 64 to a float 66. The float 66 is annular in section, having formed longitudinally therethrough a hole 68 slightly larger than the pipe 24 to permit the float to be mounted thereon and be guided thereby.

An alternative construction of our control is 50 illustrated in Fig. 4, the principal difference between the two modifications lying in the means of connection between the ring valve and the float. In the second form, one end of a thin walled pipe section 70 of larger inside diameter 55 than the outside diameter of the air pipe 24 is

welded as at 72 to the tubular float 66 coaxially with the hole 63 so that the float and pipe section are slideable on the air pipe 24. At the opposite end of the pipe, metal is removed to define upstanding arms 74. The upper ends of these arms may be secured to the ring valve 48 in any convenient manner such as providing perforations 78 in the arms which fit over studs 73 formed on the ring valve 48 and tubular rivets 80 press fitted over the stud 73 which prevent the arm 74 from slipping off the stud 73. The arms 74 may be offset outwardly as at 82 in order to afford proper clearance between the arms 74 and the valve body 42.

From the foregoing description the operation of our device may be readily understood. As the plunger is raised the amount of plunger wall displacing the hydraulic fluid becomes continually less and therefore the oil level gradually drops. The float 66 is so positioned with respect to the ports 46 that when the oil reaches a low level approaching the point of air escape through the opening 20 in the plunger head 18 it no longer buoys up the float and thereby permits it to drop, carrying the valve ring 48 with it to cover the ports 46. When the oil is at its proper and normal level the lowering of the oil level by removing the walls of the plunger from the reservoir will not cause sufficient lowering of the oil to produce a dropping of the float. The float will be continued to be buoyed up, so maintaining the valve ring in its upper position to permit the desired degree of lift of the plunger. However, should the oil supply be initially insufficient as from leakage, etc., the oil level will lower to the point of float nonsupport, whereat the valve ring descends to cover the ports 46 so preventing more air from entering the space 34.

Were the ports 46 the only openings in the body 42 a difficulty would appear. Assuming that the ports 46 are closed because the lift has reached the maximum allowable travel under the circumstances of low oil level, it will be seen that there is no way of subsequently exhausting the air from the plunger in order to lower it, and to answer this problem the open end 52 of the body 42 and ball valve 56 have been provided. The ball valve 56 and its associated seat 54 are so adjusted that appreciably higher pressure inside the valve body than outside will serve to close the valve. Thus as pressure is being admitted into the plunger the valve will normally be held against its seat so as to close this port 52 and this situation will pertain even more when the ports 46 have been closed, under which circumstance there will be maximum pressure drop across the port 52. In this fashion the ring valve operates to control the air supply substantially as if the outlet ports 46 were the only ports in the valve body. However, when the pressure is shut off or relieved in the line 24 so as to create reverse or no pressure drop across the port 52, the ball 56 will fall away from its seat so permitting an outflow of the air from the plunger.

Having thus described one embodiment of our invention, what we claim as new and useful and desire to secure by Letters Patent is:

1. Low oil control for use with a lift including a reservoir having a supply of oil therein and an open ended pipe through which air under pressure may be delivered to the surface of the oil supply to expel a portion of the oil from the reservoir, comprising in combination a cylindrical valve housing attachable to the open end of

5 the pipe and having a valve port in the cylindrical wall thereof and a relief port, a ring valve member slideable on the exterior wall of said housing and adapted to control the flow of air through said valve port, means on said housing to limit the movement of said ring valve member, a float secured to said ring valve member and responsive to changes in the oil supply level to control the position of said ring valve member so that when the oil in the reservoir falls below a predetermined level said float will move said ring valve member to port closing position, and a second valve member adapted to close said relief port when air under pressure is admitted to said housing from the pipe and to open said relief port when the pressure in the pipe is relieved.

2. Low oil control for use with a lift including a reservoir having a supply of oil therein and an open ended pipe through which air under pressure may be delivered to the surface of the oil supply to expel a portion of the oil from the reservoir, comprising in combination a cylindrical valve housing attachable to the open end of the pipe and having a valve port in the cylindrical wall thereof and a relief port, a ring valve member slideable on the exterior wall of said housing and adapted to control the flow of air through said valve port, means on said housing to limit the movement of said ring valve member, a float secured to said ring valve member and responsive to changes in the oil supply level to control the position of said ring valve member so that when the oil in the reservoir falls below a predetermined level said float will move said ring valve member to port closing position, and a valve member gravitationally movable to open position adapted to close said relief port when air under pressure is admitted to said housing from the pipe and to open said relief port when the pressure in the pipe is relieved.

3. Low oil control for use with a lift including a reservoir having a supply of oil therein and an open ended pipe through which air under pressure may be delivered to the surface of the oil supply to expel a portion of the oil from the reservoir, comprising in combination a valve housing having a smooth surfaced longitudinally extending exterior wall and being attachable to the open end of the pipe and having a valve port in said wall thereof and a relief port, a ring-like valve member longitudinally slideable on said exterior wall of said housing and adapted to control the flow of air through said valve port, means on said housing to limit the longitudinal movement of said ring-like valve member, a float secured to said ring-like valve member and responsive to changes in the oil supply level to control the position of said ring-like valve member so that when the oil in the reservoir falls below a predetermined level said float will move said ring-like valve member to port closing position, and a second valve member adapted to close said relief port when air under pressure is admitted to said housing from the pipe and to open said relief port when the pressure in the pipe is relieved.
